ELECTRIC SWITCH

John Eaton, Schenectady, N. Y., assignor to General Electric Company, a corporation of New York

Application June 5, 1943, Serial No. 489,730

8 Claims. (Cl. 200—165)

My invention relates to electric switches, more particularly to electromagnetically operated switches or contactors, and has for its object a contactor provided with simple and effective means for producing a wiping action between the contacts so as to increase the current carrying capacity of the device.

In carrying out my invention in one form, I provide two springs for holding the movable contact in position on a support moved by an operating coil, these two springs applying their forces at different points on the movable contact. The movable and stationary contact surfaces are arranged angularly so that the movable contact first touches the stationary contact at one edge thereby to effect a yielding of one of the springs and a normal rolling and wiping action on the stationary contact, after which the final movement of the armature to its attracted position effects further yielding of the first spring and also yielding of the second spring to obtain an increased contact pressure.

Preferably, the spring first to yield is relatively weak as compared with a second spring, the magnetic pull applied to the armature at that time of initial contact not being strong enough to move the armature against the force applied by the second spring. Moreover the second spring applies to its force at an edge of the movable contact opposite the point of initial contact engagement so as to provide the maximum leverage to break any weld between the two contacts at the initial point of engagement.

More specifically I provide a relatively weak helical spring which applies a force at substantially the center of the movable contact, which spring yields first, and a relatively strong flat spring which engages an outer edge of the movable contact remote from the initial point of engagement between the two contacts.

For a more complete understanding of my invention, reference should be had to the accompanying drawing, Fig. 1 of which is a plan view partly in section of an electric switch embodying my invention; Fig. 2 is a view mainly in section taken along the line 2—2 of Fig. 1 looking in the direction of the arrows; Fig. 3 is a sectional view taken along the line 3—3 of Fig. 1 looking in the direction of the arrows; Fig. 4 is a plan view of the armature and movable contact mechanism; Fig. 5 is a sectional view of Fig. 4 looking in the direction of the arrows; while Fig. 6 is a front elevation view of Fig. 4 showing one of the springs.

Referring to the drawing, I have shown my

invention in one form as comprising an operating coil 10 provided with a central magnet iron core member 11, end core pieces 12 and 13, and a magnet iron armature 14 having one end pivoted at 15 on the end core member 13. The armature 14 is biased to its unattracted position by means of a helical tension spring 17.

Secured to the armature 14 is a rigid switch arm 16. This switch arm has one end secured 10 to the armature by means of rivets 19, the switch arm and the rivet being electrically insulated from the armature by layers of insulation 18 and 18a and a cylindrical insulator 20 surrounding the rivet. The switch arm extends at right angles to the direction of movement of the armature, as shown, at right angles to the pivot axis of the armature.

Also secured to the armature is a relatively strong spring strip 21 which has one end extending between the arm 16 and the layer of insulation 18 and secured to the armature by the rivets 19. This spring extends along the switch arm but is bent away from the switch arm at an angle, and its end has a portion 22 bent at right angles toward the switch arm to a position in closely spaced relation with the side of the switch arm at its end.

The switch arm carries a bridging contact member 23 made of electrically conducting material provided with contacts 24 and 25 at its ends for engagement with stationary contacts 26 and 27. At its outer edge, i. e. the edge opposite the pivot of the armature, the bridging contact has an extension 28 provided with a V shaped groove 29 which forms an elongated bearing seat for portions 30 and 31 on the end of the spring strip 21. It will be observed that portions 30 and 31 are spaced apart to form in effect an elongated bearing in the end of the spring 21. Also, on its side adjacent the arm 16 the bridging contact is provided with two projections 32 and 33. These projections are spaced along the length of the contact arm in a direction transverse to the pivot of the armature and are on opposite sides of a central aperture 34 in the bridging contact member through which extends a pin 35 having a head 36, between which and the adjacent side of the bridging contact is a relatively weak helical compression spring 37. The pin 35 extends through an aperture provided for it in the arm 16 and is held in place by a pin 38 extending through its end and lying in a groove provided for it in the arm 16.

It will be noted that the spring strip 21 is pro-

vided with an enlarged opening through which extends the spring 21 and the pin 36, this opening defining two bent arms 39 and 40 which are connected together at their outer ends by the cross bar 41.

The bridging contact member is put in place, the pin 36 being removed, by forcing its outer edge portion between the arm 16 and the spring 21, the outer end of the spring 21 yielding somewhat thereby to seat the portions 30 and 31 on the end of the spring in the bearing groove 29. It will be observed that the spring 21 also by its engagement with the bearing 29 holds the bridging contact member 23 in transverse relation with the switch arm. The projections 32 and 33 hold the bridging contact in spaced relation with the arm. At this time the force applied by the spring 21 to the bearing seat 29 is sufficient to tilt the opposite side of the bridging contact away from the arm 16 about the projection 33 as a pivot. Next the pin 36 and spring 37 are put in place and the pressure of the spring 37 forces the inner edge of the bridging member about the projection 33 as a pivot toward the arm 16 until the projection 32 rests on the arm.

As seen in Figs. 2 and 3, the stationary contacts 26 and 27 have their contact surfaces disposed at a predetermined acute angle with the contact faces on the bridging member. Consequently, when the coil is energized and the armature moves the contact arm toward closed circuit position, the inner edges of the movable contacts, i. e., the edges adjacent the pivot of the armature, engage the stationary contacts first. Thereupon, as the armature moves toward its attracted position, the spring 37 yields to allow the bridging contact to pivot at its outer edge on the contact arm about the projection 33 in a clockwise direction as seen in Fig. 2. Also the movable contacts at the same time pivot clockwise on the stationary contacts, producing a rolling and wiping action until the contact faces are in parallel contact made engaging relation. The armature still is not quite in its fully attracted position and, in continuing its movement to the final attracted position, it moves the arm 16 away from the bridging member, which is now in engagement with the stationary contacts, thereby further compressing the spring 37 and bending the stringer spring 21. In other words, the arm 16 moves away from the outer end of the spring 21 which yields. Thus the bridging contact member is maintained in engagement with the stationary contacts by the combined forces applied by the springs 21 and 37.

It will be observed that the bearing portions 30 and 31 on the spring 21 are on opposite sides of the end of the switch arm and are spaced a substantial distance apart thereby to apply positive pressures to each of the bridging contacts 24 and 25, as contrasted with the central pressure of the helical spring 37.

One advantage of the arrangement of the two springs so that the force of one only is applied when the contacts first engage is that the force applied to the armature follows roughly the maximum pull applied to the armature during its movement. It will be understood that, as the armature moves toward its attracted position, the magnetic pull available to move it increases rapidly so that the magnetic pull available during the final movement of the armature against the forces of the two springs is many times that available at the beginning of its movement. In other words, the armature would not be actuated if it

were opposed at the beginning of its movement by the forces of the two springs. Moreover, the armature has a leverage advantage with respect to the helical spring which is nearer the pivot of the armature.

The application of the force of the stronger spring 21 to the outer edge of the movable contact, i. e., to the bearing seat 29, provides the greatest possible leverage for the force of this spring in breaking a weld between the two contacts at their inner edges where engagement is first made, in the event that a weld is formed. It will be observed that the helical spring 37 applies its force at substantially the center of the bridging contact and, therefore, has only half the leverage with respect to the inner edge of the bridging contact, as compared with the flat spring 21. Moreover, of course, the force applied by the helical spring is preferably much less than that applied by the flat spring 21. Thus, in the event of a weld at the initial point of engagement, the breaking of a weld and roll of the bridging contacts over the stationary contacts is assured by the stronger spring 21.

The various parts of the switch are supported on two parallel rectangular plates 42 and 43 made of electrically insulating material, such as a phenolic condensation product, each plate consisting of two layers, the inner layer being somewhat smaller than the outer layer and forming a support for a flexible strip covering member 44, preferably made of a fibrous insulating material, which with the two side plates encloses the operating parts of the device.

These two side plates are held in fixed relation to each other by means of right angle projections 45 and 46 on the magnet member 12 and projections 47 and 48 on the magnet member 13. Suitable screws 49—52 inclusive are provided to hold the two plates securely to these projections in parallel relation with each other, whereby also the operating coil and its stationary core members are secured to the plates themselves. To further secure it in place, the core member 12 is provided with projections 53 and 54 which extend through slots in the side plates. Similar projections 55 and 56 are provided on the core member 13, which projections extend through apertures in the side members. Also, the apertures for the projections 55 and 56 are enlarged to receive the projections 57 and 58 on the armature thereby to hold the armature in place with its lower edge, as seen in Fig. 2, pivoted on the left-hand end of the core member 13.

A stop cross bar 59 extending between the plates and secured to the plates by smaller end portions extending through openings in the plates is provided for the armature 14 when in its unattracted position, as shown in Fig. 2. A short bolt 60 extends toward the left, as seen in Fig. 2, from the center of this bar 59 and extends loosely through holes provided for it in the overlapping ends of the strip 44 and an outer cross bar 61.

The outer cross bar 61 is provided to secure the outer overlapping end of the flexible fibre strip 44, the end of the strip being secured to the cross-bar by means of rivets 61a, only one of which is shown. A nut 62 on the bolt 60 holds a cross bar 61 in place. Another cross bar 62a is secured to the inner overlapping end of the strip 44 by means of rivets. This cross bar 62a is similar in construction to the cross bar 61, and likewise has small ends mounted in slots in the outer edges of the side members 42 and 43.

Terminals 63 and 64 secured to the side plates

are provided for the ends of the operating coil 10. Also, similar terminals 65 and 66 are provided for the stationary contacts. As shown in Fig. 3, the two stationary contacts are mounted on the lower ends of two L-shaped members 67 and 68, which ends extend through apertures provided for them in the side plates 42 and 43.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States, is:

1. A switch comprising a switch member, means for moving said switch member between open and closed circuit positions, a movable contact movably mounted on said switch member, a first spring applying a force to said movable contact thereby to bias said movable contact against said switch member, a stationary contact arranged to be engaged by said movable contact when said switch member is moved toward said closed circuit position, said stationary contact having its contact surface at an angle with the contact surface of said movable contact so that edges of said contacts first engage each other and said spring yields to provide a preliminary rolling action of said movable contact on said stationary contact, and a second spring applying a force to the opposite edge of said movable contact to hold said opposite edge against said switch member during said rolling action and yielding to apply an increased contact maintaining force during a predetermined final movement of said switch member to its closed circuit position.

2. A switch comprising a pivoted switch arm, a movable contact movably mounted on the movable other end of said switch arm, a first spring applying a force to said movable contact at substantially its center thereby to bias said movable contact against said switch arm, a stationary contact arranged to be engaged by said movable contact when said switch arm is moved in one direction, said stationary contact having its contact surface at an angle with the contact surface of said movable contact so that inner edges of said contacts adjacent the pivot of said switch arm first engage each other and said spring yields to provide a preliminary rolling action of said movable contact about its inner edge on said stationary contact and about its outer edge on said contact arm to a final contact made position, and a second spring on said switch arm applying a force to said outer edge of said movable contact to hold said outer edge against said arm during said rolling action and yielding to apply an increased contact maintaining force during a predetermined final movement of said switch arm.

3. A switch comprising a switch arm, a movable contact mounted on the movable other end of said switch arm, a first spring biasing said movable contact against said switch arm, a bearing seat on an outer edge of said movable contact, a second spring secured to said arm at one end and having its other end seated in said bearing seat, and a stationary contact arranged to be engaged by said movable contact having its contact surface at an angle with the contact surface of said movable contact so that an edge of the said movable contact surface opposite said

one edge first engages said stationary contact upon movement of said switch arm in one direction to provide a rolling action and compression of said first spring after which said second spring is compressed upon continued movement of said switch arm.

4. A switch comprising a switch arm, a bridging contact mounted on said switch arm, a first spring biasing said bridging contact against said switch arm, an elongated bearing seat on one edge of said bridging contact, a second spring secured to said switch arm at one end and having its other end transversely elongated and seated in said bearing seat to hold said bridging contact in transverse relation with said switch arm and apply a force to said one edge of said bridging contact in the same direction as the force applied by said first spring but greater than the force applied by said first spring, and stationary contacts arranged to be engaged by said bridging contact, said stationary contacts having their contact surfaces at an angle with the contact surfaces on said bridging contact so that upon movement of said switch arm in one direction edges of the latter contact surfaces opposite said one edge engage said stationary contacts first thereby to provide a rolling action and compression of said first spring and then compression of said second spring upon continued movement of said switch arm.

5. A switch comprising a rigid switch arm, a pin secured to the movable end of said switch arm extending at right angles with said switch arm and in the direction of movement of said movable end, a movable contact on said movable end provided with a central aperture through which said pin extends, a helical compression spring on said pin biasing said movable contact against said switch arm, a bearing seat on one edge of said movable contact, a second spring having one other end seated in said bearing seat to apply a force to said movable contact in the same direction as said helical spring, said second spring applying a greater force than said helical spring, and a stationary contact arranged to be engaged by said movable contact when said coil is energized, said stationary contact having its contact surface at an angle with the contact surface on said movable contact so that upon movement of said switch arm in one direction an edge of the latter opposite said one edge engages said stationary contact first to provide a rolling action and compression of said helical spring and then yielding of said second spring upon continued movement of said switch arm.

6. A switch comprising a switch arm, a flat first spring having one end secured to said switch arm and its other end extending laterally at substantial right angles with the movable end of said switch arm to a position in closely spaced relation with said movable end, a contact member mounted on the movable end of said arm, a bearing seat for the end of said first spring on the outer edge of said contact member whereby said first spring biases said outer edge toward said arm, a second spring bearing on said contact member thereby to force said contact member about said first spacing member to a predetermined spaced relation with said arm, a third spring for biasing said switch arm to a predetermined circuit position, a stationary contact having a contact surface at an angle with a contact surface on said contact member so that upon movement of said switch arm in one direction the inner edges of said surfaces engage each other

first thereby causing pivotal movement of said contact member on said arm against the force applied by said second spring into parallel engaging relation with said stationary contact, and said contact arm being arranged to move away from said contact member during the final movement of said switch arm in said direction so that said movable contact member is held against said stationary contact member by the forces applied by said first and second springs.

7. A switch comprising a rigid switch arm, a flat first spring having one end secured to said switch arm and its other end extending laterally at substantial right angles with the movable end of said switch arm to a position in closely spaced relation with said movable end, a contact member mounted on the movable end of said arm, a pair of spacing members between said contact member and said arm spaced apart along the length of said arm, a bearing seat for the end of said first spring on the outer edge of said contact member whereby said first spring biases said outer edge toward said arm with the outermost of said spacing members in engagement with said arm, a second spring bearing on said contact member thereby to force said contact member about said first spacing member to a predetermined spaced relation with said arm determined by said second spacing member; a third spring for biasing said switch arm to a predetermined circuit position, a stationary contact having a contact surface at a predetermined angle with a contact surface on said contact member so that upon movement of said switch arm to another position the inner edges of said surfaces engage each other first thereby causing pivotal movement of said contact member on said first spacing projection against the force applied by said second spring into parallel engaging relation with said stationary contact, and said switch arm being arranged to move away from said contact member during the final movement of said switch arm to said other position so that said movable

contact member is held against said stationary contact member by the forces applied by said first and second springs.

8. A switch comprising a switch arm, a first spring having one end secured to said switch arm and extending along said switch arm with its other end extending laterally at substantially right angles with the end of said switch arm to a position in closely spaced relation with the end of said switch arm, a bridging contact member mounted on said end of said arm extending cross-wise thereof, a pair of projections on said bridging member at substantially its middle spaced apart along the length of said arm, a bearing seat for the end of said first spring on the outer edge of said bridging contact whereby said first spring biases said outer edge toward said arm with the outermost of said projections in engagement with said arm, a second spring bearing on said bridging member thereby to force the other of said projections into engagement with said switch arm against the force applied by said first spring, a third spring for biasing said armature to its unattracted position and said switch arm to its open circuit position, spaced stationary contacts in position to be engaged by opposite ends of said bridging member when said switch arm is moved in one direction toward a closed circuit position, said stationary contact surfaces being positioned at an angle with the contact surfaces on said bridging member so that the inner edges of said surfaces engage each other first thereby causing pivotal movement of said bridging member on said outer projection against the force applied by said second spring for flat engagement of said contact surfaces, and said stationary contacts being positioned to provide for movement of said switch arm away from said bridging member against the forces applied by said first and second springs when said switch arm moves to its final closed circuit position.

JOHN EATON.
